(57) **CLAIM**

The ornamental design for a counter top display unit, as shown and described.

DESCRIPTION

FIG. 1 is a perspective view of the counter top display unit showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof;

FIG. 7 is a bottom view thereof; and,

FIG. 8 is an exploded view thereof.

The elements shown in broken lines depict environmental structure only and form no part of the claimed design.
